Primary Examiner — Catherine R Oliver-Garcia(74) *Attorney, Agent, or Firm* — Dale J. Ream(57) **CLAIM**

The ornamental design for a belt clip battery holder, as shown and described.

DESCRIPTION

FIG. 1 is a perspective view of a belt clip battery holder showing my new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.
